2,026,785

PHOSPHORIC ACID ESTERS OF FATTY
ACID MONOGLYCERIDES

Benjamin R. Harris, Chicago, Ill.

No Drawing. Application January 8, 1934,
Serial No. 705,825

26 Claims. (Cl. 260—99.20)

My invention relates to a new class of chemical substances. It relates more in particular to a class of chemical substances having the properties of interface modifiers when employed in a treating bath containing textile, leather or ores.

The object of the invention is the provision of a new class of chemical substances.

Another object is the provision of a class of chemical substances adapted for use as interface modifiers.

Still another object is the provision of a treating bath employing the new interface modifiers of my invention.

The substances of my invention have many useful applications in the arts where frothing, wetting, penetrating, detergent, emulsifying, and other interface modifying functions are required. They are in general possessed of at least two groups, one having a hydrophilic function and the other having a lipophile function in the molecule. The hydrophilic function is performed primarily by a phosphate group; that is, a group containing phosphorus in the form of a phosphorus oxide acid radical, giving the molecule as a whole an affinity for aqueous materials. The lipophile group is any radical such as acyl or alkyl derived from a fatty acid or its corresponding alcohol and has a definite affinity for oils and fats. The hydrophilic phosphate group is linked to the lipophile group by means of a polyhydroxy substance of a class consisting of sugars, sugar alcohols, glycols, glycerols, polyglycerols, polyhydroxycarboxylic acids, and polyglycols. In general, an ester linkage joins the polyhydroxy substance and the phosphate group. The linkage between the polyhydroxy substance and the lipophile group may be either an ester or ether linkage.

Many of the compounds of my invention may be represented by the formula

wherein "R" is a lipophile group, "X" is the residue of a polyhydroxy substance, "Y" and "Z" are cations, and "w" is a small whole number.

More specifically, the compounds of my invention may be defined as non-nitrogenous esters of a phosphoric acid and a polyhydroxy substance wherein at least one hydroxy group of the polyhydroxy substance has its hydrogen substituted by a lipophile group. I employ the term "non-nitrogenous" to indicate that my substances are devoid of nitrogen linked directly to carbon,

The lipophile group may include any fatty acid group such as the fatty acid radicals of the following acids: caproic acid, capric, caprylic, valeric, butyric, abietic, hydroxystearic, benzoic, benzoylbenzoic, naphthoic, toluic, palmitic acid, 5 stearic, lauric, melissic, oleic, myristic, ricinoleic, linoleic acid or mixed fatty acids derived from animal or vegetable fats and fish oils such as lard, coconut oil, corn oil, cottonseed oil, partially or completely hydrogenated vegetable oils such as 10 cottonseed oil, corn oil, sesame oil and fatty acids of various waxes such as beeswax and carnauba wax; or the lipophile group may be an alkyl radical derived from an alcohol corresponding to any of the preceding acids, such as cetyl alcohol, 15 lauryl alcohol, etc.

Specific examples of polyhydroxy substances, the residues of which may serve as linkages between the lipophile groups and the hydrophilic phosphate groups are as follows: mucic acid, 20 tartaric acid, saccharic acid, gluconic acid, glucuronic acid, gulonic acid, mannonic acid, trihydroxyglutaric acid, glyceric acid, and the like, as well as carboxylic oxidation products of 25 polyglycerols which may be represented by the formulae:

and sugars such as: xylose, galactose, fructose, maltose, sorbitol, glucose, dulcitol, arabinol and other sugar alcohols such as hexahydric alcohols derived from sugars, and other substances having free hydroxy groups. The above polyglycerols and their oxidation products are produced by polymerizing glycerine, preferably by heating with about 1% of alkali at temperatures 50 55

from 250° to 260° C. for about three hours in the presence of an inert gas. This reaction mixture will give a mixture of various polyglycerols, the size of the molecules depending upon the time of polymerization. The mixtures of polyglycerols are then oxidized with mild oxidizing agents to convert at least one of the primary hydroxy groups to a carboxylic group.

Examples of substances of my invention may 10 be represented as follows:

There are several methods by means of which the materials of my invention may be made. The method employed should be determined primarily by considering the type of substance to be produced. In introducing the phosphate radical, for example, a material containing an esterifiable hydroxy group is reacted with phosphorus pentoxide, phosphoric acids, phosphorus halides, ethyl metaphosphate, phosphorus oxychloride or some other reagent capable of furnishing the elements of phosphoric acid. Either one or more phosphate radicals may be introduced, depending upon the substance desired. A condensing agent and/or a solvent may be added where required.

As a specific example, 7 parts of monostearin glycerol (monostearine) are dissolved in 35 parts of dry pyridine. To this solution are added, with simultaneous cooling, 12 parts of phosphorus oxychloride dissolved in 50 parts of dry acetone, the mixture being stirred meanwhile. This mixture is allowed to stand over night and it is then thrown into 300 parts of water with stirring. A precipitate forms at first, but after a few moments this becomes completely dispersed. On warming to about 60° C., the solution becomes highly colored. 15% of salt is now added to throw the product out in the form of a precipitate. This precipitate contains approximately 73% of moisture after the greater proportion of salt solution has been separated therefrom. The product may be used in this form or it may be further washed or otherwise purified. It may be dried or not, as desired. The product so formed is primarily a double glycerine ester in which one hydroxy group is esterified with a stearic acid radical and another hydroxy group is esterified with phosphoric acid. The monolauric ester glycerine phosphate may be prepared in a similar manner, but using substantially pure lauric acid, or the fatty acids of coconut oil containing about 40% lauric acid in preparing the monoglycerides which are to be subsequently reacted with phosphorus oxychloride. The resultant product is neutralized with sodium bicarbonate to produce the sodium salt. This procedure for the preparation of phosphoric esters is a conven-

ient method for making certain materials of my invention which are represented by Nos. 3, 4, 6, 7, 5 11 and 13 in the list of examples shown hereinabove, as well as others, bearing in mind that particularly where secondary phosphates are concerned (such as Nos. 4, 11, 13 in the list of examples shown hereinabove) the phosphorus oxychloride must be added gradually to the reactant with the hydroxy group, so that the latter is always present in excess throughout the course of the reaction.

According to another example, 66 parts of monobutyl ether of diethylene glycol are mixed with 58 parts of phosphorus pentoxide. This is 15 accomplished best by adding the phosphorus pentoxide gradually and in small portions to the monobutyl ether of diethylene glycol with stirring, cooling somewhat if necessary to avoid excessive heating. This mixture is allowed to re- 20 main at room temperature for about half an hour. The mixture is then taken up with about 800 parts of cold water and 20 parts of barium chloride stirred in, the latter being in the form of a 10% aqueous solution. 125 parts of salt are 25 now dissolved in this mixture. The entire mixture is allowed to remain at rest until the product floats to the surface, whereupon the brine is withdrawn and discarded. The product may be used in this form or it may be filtered or concentrated 30 further or otherwise treated, as desired. The finished product, the principal portion of which may be represented by No. 7 in the list of examples shown hereinabove, is easily dispersible in water and exhibits many useful colloidal properties 35 and particularly as an interface modifier.

While all of the substances of my invention fall into the category of interface modifiers, they modify the interface in various ways and to various extents, depending upon the relative potencies of the hydrophile and lipophile groups, the resultant of the two representing the interfacial function of the molecule as a whole.

For example: the barium salt of the butyl ether of diethyleneglycol phosphate (No. 7 of the illustrative examples given above) and diolein phosphate (No. 9 of the list of illustrative examples given above) serve well to show how the properties of my interface modifiers may vary. No. 7 is predominantly hydrophilic, practically 45 freely soluble in water; whereas, No. 9 is predominantly lipophilic, imbibes cold water but cannot be said to disperse therein. The latter does, however, disperse in hot water, particularly readily in the presence of a very low concentration 50 of electrolyte such as sodium chloride. It is well to note that the hydrophile group in both cases is essentially the same, but the lipophile group in the case of No. 9 contains approximately five times as many carbons, if not more, than the lipophile group in No. 7. No. 9 is predominantly lipophilic; No. 7 is predominantly hydrophilic, though each possesses both hydrophile and lipophile properties. No. 9 when touched with moist fingers appears greasy; whereas No. 7, as stated 55 above, is practically water soluble. No. 9 promotes water in oil emulsions; No. 7 promotes oil in water emulsions. Between such two relatively extreme examples may be inserted a series of other examples in the order of diminishing hydrophile characteristics starting with No. 70 7 upward and, per contra, with increasing lipophile characteristics working up to No. 9 and beyond. Between two vicinal members of such a series, the differences may be only very slight, 75 becoming more appreciable the further removed

any two selected members of the series are from each other.

While the illustrative examples listed hereinabove represent principally single substances, it must be understood that the invention is by no means limited to single substances. Indeed, in practice, it is frequently more convenient to prepare a mixture of the substances of my invention and use such a mixture. For example, I may 5 prepare a mixture of diglycerides by any convenient method, such as described hereinbelow and then introduce into each member of this mixture of diglycerides a phosphate radical by a convenient method.

Example:—Preparation of mixture of diglyceride phosphates from corn oil.

Heat a mixture of 880 parts of corn oil and 50 parts of glycerol in an inert atmosphere with stirring to 220° C. Add 0.88 part of flake caustic soda. Raise the temperature to 250° C., continue stirring and heat at 250° C. or thereabout for two hours. Cool to room temperature in an inert atmosphere. This product is essentially a mixture of diglycerides.

To 200 parts of the above product dissolved in 600 parts of isopropyl ether (free of alcohol and water) add 50 parts of phosphorus pentoxide and heat under reflux with stirring for three hours to 60° C., taking care to keep the reaction mixture out of contact with atmospheric moisture.

Now free this reaction product of ether, preferably by distillation.

The residue is a somewhat sirupy, oily material which may be used as such, or it may be neutralized with gaseous ammonia or aqueous ammonia or other alkaline agents. Also, the product may be washed by salting it out with brine several times, purified, or otherwise treated if desired. It consists in the main of a mixture of 40 diglyceride phosphates, the significant, predominant constituent of which is represented by No. 9 in the list of examples hereinabove.

In place of corn oil in the above, I can use cotton seed oil, peanut oil, sesame oil, sunflower oil, neat's-foot oil, coconut oils, hydrogenated oils, lard, tallow, etc., cod oil and other common triglycerides.

If, on the other hand, it is desired to prepare a single substantially pure substance analogous 50 to the above, it is only necessary to treat diolein with phosphorus pentoxide as described above.

This procedure, for introducing phosphate radicals, described directly above, I have also successfully used in the preparation of materials 55 represented by Nos. 1, 2, 5, 6, 8, 10, 12, 14, 15, and 16 in the list of examples shown hereinabove, as well as others. It is, of course, obviously within the skill of any qualified chemist to compute molal or multiples of molal proportions of the 60 reactants with respect to each other.

The products above described may be added in suitable proportions to a treating bath containing an aqueous medium, with or without an additional substance, such as for example alkalies, mordants, dyes, color discharging reagents, H₂O₂, color reducing agents, oils, sulphonated oils, mordanting salts, fabrics and other reagents or substances used in treating baths, and the treating bath so formed can be employed 65 with satisfaction in all of the arts in which interface modification is desired. For example, dyeing, bleaching, scouring, leather stuffing, and otherwise treating fabrics, fibers and other materials in a treating bath of this character is pro- 70 75

ductive of good results. Also in the stuffing of leather, dyeing, and otherwise treating furs, and in many other arts, a treating bath employing the materials of my invention may be used. In flotation of ores it may be used in connection with other reagents to modify the interface between the finely divided ore and the aqueous medium.

10 While I have described several methods for the preparation of the materials of my invention, it must be understood that the scope of the invented class of substances is by no means limited by these methods. Other convenient methods may be used. This also applies, and particularly so, to supplementary procedures of purification or isolation which lie strictly within the province of skill of any qualified chemist whose procedures in each instance must be governed by the properties of the materials concerned, and by the degree or the character of the purity desired.

The term "residue", as used throughout the specification and claims, is employed in its ordinarily understood chemical significance. For example, where one of the hydroxyl groups of glycerine is esterified with a fatty acid or etherified with an alcohol and another of the hydroxyl groups of the glycerine is esterified with a phosphoric acid, that which remains of the glycerine molecule, for example,

35 is the "residue" of the polyhydroxy substance, in this case glycerine.

What I claim as new and desire to protect by Letters Patent of the United States is:

40 1. A non-nitrogenous hydrophilic ester of phosphoric acid with lipophile and hydrophile groups, said ester being represented by the formula

wherein "R", the lipophile portion of the molecule, is an acyl radical and has at least four carbon atoms, "X" is a glycol residue, "Y" and "Z" represent cations, and "w" is an integer.

2. A hydrophilic ester of phosphoric acid with lipophile and hydrophile groups, said ester being represented by the formula

wherein "R" is a higher fatty acid radical, "X" is a glycerol radical, "Y" and "Z" represent cations, and "w" is an integer, and the remaining OH of the glycerine is free and unesterified.

65 3. A non-nitrogenous phosphoric acid ester of a polyhydroxy substance wherein the polyhydroxy substance has only one hydroxy group in which the hydrogen has been replaced by an acyl group with at least four but less than eighteen carbon atoms.

4. A non-nitrogenous phosphoric acid ester of
70 a polyhydric alcohol wherein only one hydroxy
group of the alcohol has its hydrogen replaced
by an acyl group with at least four but less than
eighteen carbon atoms.

5. A non-nitrogenous phosphoric acid ester of
75 a polyhydric alcohol wherein only one hydroxy

group of the alcohol is esterified by a fatty acid with at least four but less than eighteen carbon atoms.

6. A non-nitrogenous phosphoric acid ester of a hexahydric alcohol derived from sugar wherein the hexahydric alcohol derived from sugar has at least one hydroxy group in which the hydrogen is replaced by a lipophile group.

7. A non-nitrogenous phosphoric acid ester of sorbitol wherein the sorbitol has at least one hydroxy group in which the hydrogen is replaced by a lipophile group. 10

8. A phosphoric acid ester of a fatty acid monoglyceride, the fatty acid radical having at least four carbon atoms.

9. A non-nitrogenous hydrophilic ester of phosphoric acid with lipophile and hydrophile groups, said ester being represented by the formula

wherein "R", the lipophile portion of the molecule, is an acyl radical and has at least four carbon atoms, "X" is the residue of an aliphatic polyhydroxy substance with at least two esterifiable hydroxy groups, "Y" and "Z" represent cations, and "w" is an integer.

10. A non-nitrogenous hydrophilic ester of phosphoric acid with lipophile and hydrophile groups, said ester being represented by the formula

wherein "R", the lipophile portion of the molecule, is an acyl radical and has at least four carbon atoms, "X" is the residue of a polyhydric alcohol, "Y" and "Z" represent cations, and "w" is an integer.

11. A non-nitrogenous hydrophilic ester of phosphoric acid with lipophile and hydrophile groups, said ester being represented by the formula

wherein "R", the lipophile portion of the molecule, has at least four carbon atoms, "X" is a glycerol residue, "Y" and "Z" represent cations, and "w" is an integer.

12. A non-nitrogenous hydrophilic ester of phosphoric acid with lipophile and hydrophile groups, said ester being represented by the formula

wherein "R", the lipophile portion of the molecule, has at least four carbon atoms but not more than eighteen, "X" is a glycerol residue, "Y" and "Z" represent cations, and "w" is an integer.

13. A non-nitrogenous phosphoric acid ester of a glycerol wherein the glycerol has one hydroxy group in which the hydrogen is replaced by a lipophile radical, another hydroxy group wherein the hydrogen is replaced by a hydrophile phosphate radical, and wherein the remaining hydroxy group is replaced by a hydrophile radical.

- droxy group is free and unesterified, said ester having hydrophilic properties.
14. A non-nitrogenous phosphoric acid ester of a polyhydric alcohol, wherein the hydrogen of only one hydroxy group of the alcohol is replaced by a lipophile acyl group with at least four carbon atoms, said ester having hydrophile properties.
15. A non-nitrogenous phosphoric acid ester of a glycerol, wherein the glycerol has only hydroxy group in which the hydrogen is replaced by a lipophile acyl group with at least four carbon atoms, said ester having hydrophile properties.
16. A non-nitrogenous phosphoric acid ester of a fatty acid monoglyceride wherein at least one fatty acid radical is that of a normally liquid fatty acid.
17. A non-nitrogenous ester of phosphoric acid and an aliphatic polyhydroxy substance with at least two esterifiable hydroxy groups, wherein the hydrogen of at least one hydroxy group is replaced by a hydrophile phosphate radical, wherein the hydrogen of only one other hydroxy group is replaced by a lipophile radical, and wherein the lipophile portion of the molecule contains an acyl radical which contains at least four but less than 36 carbon atoms, said ester having hydrophilic properties.
18. A non-nitrogenous ester of phosphoric acid and an aliphatic polyhydroxy substance with at least two esterifiable hydroxy groups, wherein the hydrogen of at least one hydroxy group is replaced by a hydrophile phosphate radical, wherein the hydrogen of only one other hydroxy group is replaced by a lipophile radical, wherein the lipophile portion of the molecule contains at least four but less than 36 carbon atoms, said ester having hydrophilic properties, and wherein at least one hydrogen of the phosphate radical is replaced by a cation.
19. A non-nitrogenous phosphoric acid ester of glycerol having a hydrophile phosphate group esterified at one hydroxy group, and a lipophile group replacing one hydrogen of only one the remaining hydroxy groups, the lipophile portion
- of the molecule having less than 36 carbon atoms.
20. An ester of phosphoric acid and an aliphatic dihydroxy substance, wherein the hydrogen of one hydroxy group is replaced by a hydrophile phosphate radical and wherein the hydrogen of the other hydroxy group is replaced by an acyl radical with at least four carbon atoms, but not more than 18 carbon atoms.
21. A non-nitrogenous ester of phosphoric acid and an aliphatic polyhydroxy substance with at least four carbon atoms and with at least two esterifiable hydroxy groups, wherein the hydrogen of at least one hydroxy group is replaced by a hydrophile phosphate radical, wherein the hydrogen of at least one other hydroxy group is replaced by a lipophile radical and wherein the lipophile portion of the molecule comprises an acyl radical which contains at least four carbon atoms, said ester having hydrophile properties.
22. A non-nitrogenous ester of phosphoric acid and an aliphatic dihydroxy substance, wherein the hydrogen of one hydroxy group is replaced by a hydrophile phosphate radical and wherein the hydrogen of the other hydroxy group is replaced by an acyl radical with at least four carbon atoms, said ester having hydrophile properties.
23. A non-nitrogenous phosphoric acid ester of a polyhydroxy substance with at least two esterifiable hydroxy groups, wherein two molecules of the polyhydroxy substance are esterified with and linked through one and the same hydrophile phosphoric acid radical, wherein the hydrogen of at least one hydroxy group of the polyhydroxy substance is replaced by a lipophile radical with at least four carbon atoms, said ester having hydrophile properties.
24. A non-nitrogenous phosphoric acid ester of a fatty acid mono-glyceride.
25. A non-nitrogenous phosphoric acid ester of a fatty acid mono-glyceride, the fatty acid containing at least four carbon atoms.
26. A non-nitrogenous chemical compound of the class consisting of mono olein phosphate and alkali salts thereof.

BENJAMIN P. HARRIS. 45
